UNITED STATES PATENT OFFICE.

WILLIAM J. PATTERSON, OF BEAVER, PENNSYLVANIA.

DESIGN FOR A LAMP-CHIMNEY.

SPECIFICATION forming part of Design No. 14,587, dated January 29, 1864.

Application filed November 26, 1863. Term of patent 7 years.

To all whom it may concern:

Be it known that I, WILLIAM J. PATTERSON, of Beaver, in the county of Beaver and State of Pennsylvania, have invented and produced a new and original Design for Lamp-Chimneys, of which the following is a specification.

Reference is to be had to the accompanying drawings, forming part of this specification, in which similar letters of reference indicate corresponding parts in both figures.

Figures 1 and 2 are elevations as seen from opposite sides of a lamp-chimney, showing my improved design.

15 My new design, which is symbolical of harvest, embraces a raised ornamentation, which represents a sheaf of grain or other grass, herbage, or plants arranged to surround the upper portion of the chimney, with the stem portions of the sheaf uppermost; also, a twisted, tied, or knotted band around the sheaf; likewise, a sickle having its blade tucked into or within the band on one side of the sheaf.

25 A designates the lamp-chimney, and B a raised ornamentation on and surrounding the upper portion of the chimney, representing a sheaf of wheat or grain with stems of the plant uppermost.

30 C represents a spun or twisted raised band or binder around the stem portions of the sheaf, tied or knotted, as at b, on one side of the chimney, as if for holding the sheaf together; and D represents a sickle having its blade stuck into or within the band on one 35 side of the sheaf.

Having thus described my design, I claim as new and desire to secure by Letters Patent—

1. The design for a lamp-chimney herein shown and described, consisting of a raised ornamentation, which represents a sheaf arranged 40 to surround the upper portion of the chimney with its stems uppermost.

2. The design for a lamp-chimney herein shown and described, consisting of a raised ornamentation, which represents a sheaf arranged 45 to surround the upper portion of the chimney with its stems uppermost, and a band around the stem portions of the sheaf.

3. The design for a lamp-chimney herein shown and described, consisting of a raised ornamentation, which represents a sheaf arranged 50 to surround the upper portion of the chimney with its stems uppermost, a band around the stem portion of the sheaf, and a sickle having its blade stuck into or within the band on one 55 side of the sheaf.

4. The within-described design for a lamp-chimney, consisting of a raised ornamentation, which represents a sheaf, B, of grain arranged to surround the upper portion of the chimney 60 with its stems uppermost, a band, C, around the stem portion of the sheaf, tied or knotted, as at b, on one side of the chimney, and a sickle, D, on another side of the chimney, with its blade stuck into or within the band 65 on the outside of the sheaf, substantially as shown.

WILLIAM J. PATTERSON.
